UNITED STATES PATENT OFFICE.

FRED DUNCAN, OF SUMMIT, OREGON.

TIE-PLATE.

Application filed February 10, 1928. Serial No. 253,463.

This invention relates to rail tie plates, and its general object is to provide a tie plate for railroad rails, that prevents the same from creeping longitudinally or moving laterally, but allows expansion thereof, with the result, the rails will be retained in a true uniform manner at all times, therefore preventing accidents as well as saving time and labor in upkeep and the like.

10 A further object of the invention is to provide a tie plate of the character set forth, that is easily applied to a rail, is inexpensive to manufacture, simple in construction and efficient in operation and service.

15 This invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like or 25 corresponding parts throughout the several views, and in which:

Figure 1 is a top plan view showing the tie plate which forms the subject matter of the present invention in use.

30 Figure 2 is a sectional view taken approximately on line 2—2 of Figure 1.

Figure 3 is a sectional view taken approximately on line 3—3 of Figure 2, looking in the direction of the arrows.

35 Figure 4 is a perspective view of the tie plate per se.

Referring to the drawings in detail, the reference numeral 1 indicates the base of the tie plate, which as best shown in Figure 4 of 40 the drawings is rectangular in formation and is flat with spike receiving openings 2 arranged adjacent the ends thereof.

Extending laterally from the sides of the plate adjacent one end thereof are lugs which 45 are bent upwardly upon themselves to provide uprights 3. The lugs have one of their side faces flattened as at 4 while the top and other sides thereof are curved.

Rising from the sides adjacent the opposite 50 end of the base are arms 5 which have their upper portions disposed at an upward inclination toward the lugs. The upward portions for distinction are indicated by the reference numeral 6 and have their under 55 sides rounded as at 7.

From the above description and disclosure

of the drawings, it will be obvious that I have provided a tie plate which is adapted to receive a rail in a manner whereby the same is supported thereon with one longitudinal edge of the base flange in contacting engagement with the flattened sides of the lugs, while the arms 5 have their rounded undersides disposed in contacting engagement with the top of the opposite side of the base flange as 60 clearly shown in Figures 2 and 3 of the drawings. Due to the length of the arms 5, they will be substantially resilient, with the result they act to clamp the rail upon the base as will be apparent but will allow for a sufficient amount of expansion, and therefore prevent damage to the rail and at the same time cooperate with the lugs to prevent lateral movement. While the arms provide expansion, they will of course substantially prevent 65 longitudinal movement of the rails as set forth.

The tie plates do not necessarily have to be arranged on each tie of the rails, but they should be utilized adjacent the rail joints as 80 shown in Figure 1, and are secured to the ties through the medium of spikes 8 passing through spike receiving openings 2. In applying the plates to the rails, the latter can be lifted and the plates forced thereon as will 85 be apparent.

It is thought from the foregoing description that the advantages and novel features of my invention will be readily apparent.

I desire it to be understood that I may 90 make changes in the construction and in the combination and arrangement of the several parts, provided that such changes fall within the scope of the appended claims.

What I claim is:

1. A tie plate of the character described comprising a rectangular base provided with spike receiving openings arranged in pairs adjacent the ends of said base, lugs extending from the sides of said base adjacent one end thereof and having one of their sides flattened, arms extending from the sides at the opposite end of said base and terminating in upper portions disposed toward said lugs for cooperation therewith for securing the rail 105 on said base.

2. A tie plate of the character described comprising a base of rectangular flat formation and being provided with openings arranged in pairs adjacent the ends thereof, said 110 base being adapted to support a rail, lugs extending from the sides adjacent one end of the

- base, uprights included in said lugs which have one of their faces flat, arms rising from the sides adjacent the opposite end of said base and including upper portions disposed 5 toward the lugs with rounded under sides adapted to be disposed in contacting engagement with the base flange of a rail in a manner to cooperate with the lugs for securing the rail upon the base.
- 10 3. A tie plate of the character described comprising a rectangular base provided with openings arranged in pairs adjacent the ends thereof, lugs extending laterally from the

base adjacent one end thereof and including upright portions, said lugs having one of their faces flattened, arms rising from the base at its opposite end, inclined upper portions included in said arms and being disposed toward the lugs, and said upper portions being provided with rounded lower surfaces adapted to be disposed in clamping engagement with the base flange of a rail for the purpose of cooperating with the lugs for securing the rail upon the base.

In testimony whereof I affix my signature.
FRED DUNCAN.
